UNITED STATES PATENT OFFICE.

WILLIAM C. CUTLER, OF NORTH GLENDALE, CALIFORNIA.

AUTOMATIC INFORMATION DEVICE.

1,384,306.

Specification of Letters Patent. Patented July 12, 1921.

Application filed February 3, 1921. Serial No. 442,243.

To all whom it may concern:

Be it known that I, WILLIAM C. CUTLER, a citizen of the United States, residing at North Glendale, in the county of Los Angeles and State of California, have invented 5 a new and useful Automatic Information Device, of which the following is a specification.

This invention relates to devices for holding 10 tabled and classified matter in a stored position ready to move into a convenient position for inspection when the automatic operating mechanism is so set.

One of the objects of this invention is 15 to securely lock and hold the operating and lifting mechanism in a certain position as long as one of the tables is in lifted position.

Another object is to prevent any operating 20 or any moving of any of the operating mechanism as long as one of the inner parts is away from its normal storing position after the operating mechanism has once been moved to such an extent.

25 Another object is to provide a device which will be reliable and not liable to get out of working order.

Another object is to provide such a device with a pedal that will stay down near 30 its lowermost position when once so moved until any card that may have been lifted has come back to its storing position, so that no vibrating or undue movement can be transmitted to such card.

35 Another object is to provide means for automatically releasing the pedal from such lowermost position as soon as the lifted card has reached its storing position.

Another object is to provide means, allowing 40 a moving of the pedal only once while bringing a card up to displaying position when the pedal becomes locked until the card has reached its original storing position.

45 Another object is to provide locking means for the lifting and setting mechanism, to lock one mechanism when the other is being operated.

Other objects will appear from the following 50 description and appended claims as well as from the accompanying drawings, in which—

Figure 1 is a perspective outside view of the device.

55 Fig. 2 is an end elevation of the device.

with only the end wall of the casing taken away.

Fig. 3 is a vertical sectional view of the device on line 3—3 of Fig. 2.

Fig. 4 is a detail top plan view of one 60 of the end portions of the lifting hooks.

Fig. 5 is a front elevation of the hook in Fig. 4.

Fig. 6 is a vertical cross section on line 65 6—6 of Fig. 5.

Fig. 7 is an end elevation of the interlocking and engaging means in operative relation to the foot pedal of the lifting mechanism, in slightly modified form.

Fig. 8 is a top plan view of the mechanism in Fig. 7, shown in operative relation 70 to one of the side walls of the casing or cabinet of the device.

Fig. 9 is a diagrammatic illustration of the balancing and equalizing means for the 75 table carriers in end elevation.

The cabinet 9, illustrated in Fig. 1 in perspective, normally consists of a rear wall 10, see Fig. 2, side walls 11, front wall 12, top 13, glassed upper front 14, and the desk-like front piece 15.

A setting termination is preferably provided in or near the desk-like front, as indicated at 16. A lifting termination is preferably provided in the front, as indicated 85 at 17. Both terminations must naturally be on the outside of the device so that the device can be operated and used from the outside and without having to open any part of the device. Having the whole device normally closed tends to help to protect the working mechanism from being tampered with. To fully protect the inner mechanism against unjustified and unauthorized meddling and tampering, such portions of the 95 mechanism that extend to the outside must naturally be of such a size and construction as not to allow undue influence of the inner mechanism through the outer terminations, and there must be safety means close 90 enough to the outside within the device which protect as far as possible the inner mechanism.

The desk-like portion of the front is in a position to be used for writing and making notes. On the other hand, this desk portion is preferably provided with the index for the device, as indicated at 18. Since the device is intended to be used for a city directory, business directory, and other de- 105 110

sirable tabled information holding device, it is naturally necessary that the tabled and stored matter must be indexed so that any one desirous of obtaining a certain class of 5 classified matter may know how to cause the device to disclose or display such matter. Certain matter may, for instance, be on a common table indexed "a." This "a" appears also in the line, indicated at 19 10 along the slot 20, so that the indicating point 21 of the setting termination 16 can be set near such a point or place. Having the button 16, (the termination may easily be in form of a button, knob, handle and 15 any other similar handy form) set near a certain letter or indicating mark in the line 19, means that one of a set of tables has been chosen by such a setting. If the foot 20 pedal 17 is then operated, such a chosen table appears behind the upper glassed front 14 so that the printed or otherwise arranged matter may be seen behind the glass.

The operation of the device is best understood from the illustration in Fig. 2, and 25 Fig. 3 may be considered from time to time in conjunction with Fig. 2.

Tables to show classified and indexed matter may best be provided on plates or 30 cards 22, see Figs. 2 and 3. Such cards are suspended between two movable frames 23, see Fig. 3, so that the cards retain a hanging position no matter how and to what position the frames are moved, see Fig. 2. Stay-bolts 24 are provided between the two 35 frames 23 so that the whole will operate as one frame, swingably mounted on the end bolts 25. The connecting rod 26 connects the frame with the setting button 16. A moving of the button 16 produces a swinging 40 of the frame on the bolts 25, thereby moving the arch-shaped portions 27 of the frame in the path of a circle. The edges of the arch-shaped portions of the frame are provided with notches or pockets 28 for receiving and supporting the rods 29 of the 45 cards 22.

The cards are lifted from the frame at the highest point of the frame, indicated at 30.

The illustration in Fig. 2 makes it clear 50 that the stay-bolts 24 are so arranged that the cards can hang in a practically vertical line at any point on the frame. The movement of the button 16 in the slot 20 means a direct movement of the cards on the arch-shaped portions of the frame.

A dashpot 31 is connected to the frame at 55 32 for controlling the movement of the frame. A ratchet bar 33, of nearly the form of the arch-shaped portions of the frame, is secured to the frame at 34 and 35 and 60 bridged over the bar 26, so that the main portion of the ratchet bar is spaced from the arch-shaped portion of the frame to which it is secured. Since both arch-shaped portions 65 of the frame are rigidly inter-connected by

the stay-bolts 24, only one operating bar 26 is necessary, and also only one ratchet bar for setting the frame in certain desired and chosen positions. A bar 36 is provided with a selecting and adjusting cam 37 to engage 70 with one of the notches 38 of the ratchet bar 33. The cam 37 serves to automatically adjust the frame one way or the other so that one of the cards is adjusted positively into a lifting position. It will easily be 75 understood that the frame may not be exactly in a position to bring one certain card into the correct lifting position when the setting button 16 is shifted to near a certain indicating mark on the desk, so that the 80 lifting mechanism would not be able to select any card, the lifting member eventually being just between two cards. To avoid this, the ratchet arrangement is provided so that the cam will force itself into one of the 85 cams or notches of the ratchet bar, even if the frame should thereby automatically be moved to a position not desired. The cam 37 is for adjusting to the correct position of one of the cards; normally this is to the 90 card indicated by the mark on the desk nearest to the indicating point 21 on the knob 16. A locking pawl 39 is provided, having an engaging point 40 to engage with the notches 41 in the ratchet bar 33. The 95 pawl 40 is automatically operated by the spring 42, as soon as the pin 43 on the rod 36 moves away from the pawl.

The rod or bar 36 connects to the foot 100 pedal 17, as indicated at 44, and the least movement of the pedal downwardly allows the pawl to engage with the ratchet bar 33.

In case that the ratchet bar 33 is not in a 105 position that the point 40 can slip into engagement with one of the teeth 41 of the ratchet bar 33, the cam 37 will on further downward movement of the pedal by the force of the pedal be caused to adjust the position of the ratchet bar 33 so that the 110 pawl can enter one of the teeth 41. The 115 pawl 39 is suitably supported on the side wall of the cabinet by the pin 45 or other similar suitable means. The bar 36 with the cam 37 is also suitably guided by the side 120 wall of the cabinet, as indicated at 46 in Fig. 3, so that the ratchet bar 33 and thereby the frame for the several stored cards, when engaged by the bar 36 is and can be held in certain relation to the cabinet so as to establish a certain lifting position 30 from 125 which a chosen card may be lifted.

A card lifting hook 47 is provided in a position on each end of the chosen card, that is near the lifting position so that the ends of the pins or supporting rods 29 of the cards 130 can pass through the hooks when swung on the frame ready to engage with the card at the top point or highest point on the frame, that is at the lifting point 30. The hooks 47 are illustrated in end view in Fig. 2, and in 135

rear side elevation in Fig. 3, showing that the hooks are suspended on the members 48. The two hooks are joined by a common bar 49, adjustable by a buckle (commonly known as turnbuckle) 50, see Fig. 3. Each of the hook members is provided with a downwardly projecting end 51 in a position out of reach of the ends of the supporting rod 29 of the cards, and another centrally projecting end 52 in a position to reach below the ends of the supporting rods 29, so that the ends of the supporting rods of the cards can pass through the hooks without touching the hooks when the hooks are in their inoperative position, that is the lifting position of the chosen card.

In Figs. 4, 5 and 6, the hook is shown in detail, somewhat enlarged, a bore 53 being provided to receive a spring 54. A pin 55, having a cross member 56, is inserted through a smaller bore 57 from the top and through the spring 54. A block 58 is riveted or otherwise in a similar manner secured to the lower end of the pin so as to engage the spring between the hook and the block for automatically forcing the block out of hook to normally retain the position in which it is illustrated. The dotted lines in a circle, indicated at 59, in Fig. 6, make it clear that the rod ends of the supporting bar of the cards are engaged between the end 52 of the hook and the block 58. The cross member 56 is provided to come to rest on the rest members 60 provided on the walls of the cabinet, as illustrated in Fig. 3. In descending, the hooks 47 pass into resting and storing position between the rest members 60 so as to bring the cross members 56 to rest on the top edges of the rest members 60, thereby overcoming the tension of the springs 54 so as to withdraw the blocks into a position within the hooks so as to free the ends of the supporting rod 29 of the card that just returned in descending to its storing position. The frame may then again be operated for choosing another table or card, as will easily be understood from the above.

The connecting rod 61, connecting with the foot pedal, as indicated at 62, normally engages over the end 63 of the lever 64, so that, by a downward movement of the foot pedal 17, the lever 64 is also moved with the pedal. The operating lever 65 is provided on a common shaft 66 with the lever 64, so that the movement of the lever 64 is transmitted to the lever 65. A connecting rod 67 engages at 68 with the lever 65 and terminates at its upper end in sleeve-like members 69, so that an extension rod 70 may somewhat and somehow telescope in the sleeve-like portions 69 of and in relation to the lower rod 67. A shouldering piece or member 71 is provided on the rod 70 to seat or rest against the end of the rod 67, both rods being drawn together by the spring

72. A stop 73 is provided on the rod 70, normally engaged by the lever 74.

The operating of the lever 65 puts the spring 72 only under suitable tension, but does not actually move or operate the rod 70, until the very last moment when the foot pedal reaches its lowermost position, at which time the shoulder member 75 on the rod 76 presses on the end 77 of the lever 74 thereby disengaging the end 73 of the same lever 74 from the stop 73 on the rod 70. The rod 70 is then free to descend under the tension of the spring 72 controlled by the dashpot 79. The rod 76 is in connection with the foot pedal at 80 at its lower end 80 and in connection at its upper end 81 with the lever 82.

The lever 83 engages at 84 with the pulley 85. Two pulleys are naturally necessary as long as two flexible members 48 are used for lifting the cards or tables, but it is sufficient that one of the pulleys is engaged and controlled as at 84, since both pulleys 85 are on a common shaft 87, as clearly illustrated in Fig. 3. The smaller pulley 86 is also provided on the common shaft 87. The upper portion 88 of the rod 70 must then be of flexible material, or, in other words, a portion of flexible material should preferably be provided on the upper end of the rod 70. Such a flexible member is wound around the pulley 86 and suitably secured to the pulley, so that, on unwinding, the flexible member or portion does not entirely disengage from the pulley 86. The flexible member 48 is also wound each on one of the pulleys 85, and the ends of the two flexible members 48 are then also suitably secured to the pulleys 85 to not disengage entirely from the pulleys on unwinding.

A pulling and unwinding of the flexible member 88 from the pulley 86, caused by the operation of the rod 70, as described above, produces a winding of the flexible members 48 to the pulleys 85, and thereby a lifting of a card, the speed of the movement being controlled by the dashpot 79. The lifting operation of the card is then automatic after the foot pedal has caused power to become stored in the spring 72.

The descending of the card or table is preferably produced by operation of the weight of the table and of lifting hooks and cross rod or bar 49, also controlled by the dashpot 79.

From the above it is clear that the movement of the levers 64 and 65, especially in their upward movement, is also controlled by the dashpot 79.

The foot pedal, however, is moved back to its inoperative position, that is, its upper position, by the spring 91, which, of course, acts quicker than the dashpot would allow.

As described above, on pressing the foot

pedal down, the lever 64 is also pressed down, the lever 64 being controlled in its upward movement by the dashpot 79, while the foot pedal is controlled and quickly 5 snapped back by the action of the spring 91, which means that the upper termination 92 of the connecting rod 61 is pressed against the inclined upper portion 93 of the lever 64. The inclined upper portion 10 93 of the lever 64 is in its lowermost position so disposed as to cause the upward-moving upper termination 92 of the connecting rod 61 to slide to the position indicated at 94, somewhat in the rear of the bar 15 or partition block 95, disengaged from the hook-like end of the lever 64.

The upper termination of the connecting rod may be in form of a roller provided on the side of the upper end of the connecting rod 61, the roller to reach over the hook-like portion of the lever 64.

In this position of 94, the connecting rod 61 is held by the hook-like member 96 until the lifted table and therewith the levers 25 64 and 65 are in their normal inoperative position, when the pin 97 on the lever 65 comes to press against the upper end 98 of the hook member 96 thereby freeing the connecting rod 61 so that the upper portion 92 may slide upwardly between the bar 95 and the rear bar 99. The upper portion 100 of the rear bar 99 guides the upper portion 92 of the connecting rod back to its normal inoperative position above to 30 its hook-like portion of the lever 64, ready for the next action of the foot pedal.

This arrangement gives the advantage that during the descending of a card the foot pedal cannot be operated at all, so that 40 the card must first be in its normal storing position before any mechanism can be operated. The setting mechanism is locked by the foot pedal as long as the foot pedal is in its lower position, the rod 36 engaging 45 the ratchet bar 33 by the cam 37, and the pawl engaging also until the foot pedal is back in its uppermost position, that is its inoperative position. The pedal, on the other hand, as described above, is locked 50 against operation, or against being operated in the normal manner as long as the lifted card is descending. So the whole device is locked while a lifted table is descending from a lifted, information displaying or 55 disclosing position to its inoperative and storing position, as will easily be understood from the above.

The table-storing frame, being swingably mounted and supported on the end pins 25, 60 illustrated in Fig. 2 as swung toward the front of the device, may be swung to a similar extent toward the rear wall 10 so that the larger portion of the stored tables or cards hang in their stored position and condition near the rear wall,

Such a swinging of the table-storing frame with the whole tables hanging eventually on one side of its central support shows that the frame and tables have to be balanced in a suitable manner. In Fig. 3, 70 rollers or pulleys 101 are provided on one of the side walls of the cabinet and connecting means 102 and springs 103 form the balancing means for the frame and tables. An end elevation of this arrangement is 75 illustrated in Fig. 9, the corner 104 of the frame being swung over to its lowermost position thereby putting the spring 103_a under increased stress, while the corner 105 of the frame is in its uppermost position, the 80 spring 103_b being less stretched, one of the springs always counteracting the overhanging weight of the frame, as will easily be understood.

In Figs. 7 and 8 is a slightly modified 85 form of a foot pedal and operating lever interengaging. The foot pedal 17 and the connecting rod 61 are not modified over the illustrations in Figs. 2 and 3, but the lever 64 is represented by the lever 106 in these 90 Figs. 7 and 8, the lever 106 having only the hook-like engaging end and not the inclined upper portion 93 of the lever 64 in Fig. 2. The oscillating member 107 is provided 95 swingably mounted at 108, actuated by the spring 109. The upper termination 110 of the connecting rod 61 is formed to reach over the oscillating member and over the hook-like end of the lever 106 in its inoperative position. On pressing the foot pedal 100 down, as soon as the end 110 reaches the position indicated at 111, the oscillating member 110 is actuated by the spring to take its original position, now above the end 110. In moving downwardly, the end 110 slides 105 along the edge 112 of the oscillating member until the end 110 reaches the position at 111, when the oscillating member can snap or move back to its normal inoperative position. 110

As long as the foot pedal is held down, the end 110 stays engaged with the hook-like portion of the lever 106, but as soon as the foot pedal is released it moves over the end 115 of the oscillating member to the position 113 thereby freeing the lever 106 to move up to its upper inoperative position in a similar manner as described in relation to the device disclosed and illustrated in Fig. 2. The connecting rod 61 is then locked in a 120 similar manner by the hook member 96 as described in relation to Fig. 2, until the lever 65 reaches its uppermost position when the hook member is put or forced back to its normal unlocking position by the pin 97. 125 The connecting rod with the end 110 passes upwardly between the bars 114 and 115 back to its inoperative position above the hook portion of the lever 106 placing the foot pedal ready for the next downward 130

movement in a similar manner as described with reference to Fig. 2.

Having thus described my invention, I claim:

- 5 1. In an automatic information device, a series of tables, a hand lever, a foot lever, means operative by the hand lever to move any one of the tables to selective position, means operative by movement of the foot lever to move the selected table out of selective position to view position, and means for retaining the foot lever in a locked position until released by the action of the table returning to said selective position.
- 10 2. In an automatic information device, a series of tables, a table carriage, tables and carriage mounted for an oscillating movement so as to retain a hanging position for the tables at any point of the oscillating movement of the carriage, a ratchet bar near and following the segmental form of the carriage, a pawl for locking the ratchet bar and thereby the carriage against oscillating movement, operating means for moving any 15 of the tables to selective position, operating means for moving the selected table out of selective position to view position, and adjusting means for alining and locking the ratchet and therewith the table carriage in selective position against oscillating movement as long as one of the tables is moved 20 out of its storing position on the carriage.
- 25 3. In an information device, an operating lever, a foot pedal, connecting means between the operating lever and the foot pedal adapted to disengage from the operating lever in its lowermost position when moved upwardly, guiding means for holding the connecting means engaged with the operating lever in the downward movement of the lever, and guiding means for bringing the connecting means to a point above the lever when the foot pedal is completing its upward movement.
- 30 4. In an information device, an operating lever, a foot pedal, connecting means between the operating lever and the foot pedal adapted to disengage from the operating lever when the foot pedal starts to move upwardly, guiding means for holding the connecting means engaged with the operating lever in the downward movement of the lever, guiding means for bringing the connecting means to a point above the lever when the foot pedal is completing its upward movement.
- 35 5. In an information device, an operating lever, a foot pedal, connecting means between the operating lever and the foot pedal adapted to disengage from the operating lever when the foot pedal starts to move upwardly, guiding means for holding the connecting means engaged with the operating lever in the downward movement of the lever, guiding means for bringing the connecting means to a point above the lever when the foot pedal is completing its upward movement.
- 40 6. In an information device, an operating lever, a foot pedal, connecting means between the operating lever and the foot pedal adapted to disengage from the operating lever in its lowermost position when moved upwardly, guiding means for holding the connecting means engaged with the operating lever in the downward movement of the lever, means to disengage the connecting means from the operating lever when the foot pedal starts in its upward movement, means for holding the foot pedal and the connecting means near their lowermost position until the operating lever has reached its uppermost position after being disengaged, and guiding means for bringing the connecting means to a point above the lever when the foot pedal is completing its upward movement.
- 45 7. In an information device, an operating lever, a foot pedal, connecting means between the operating lever and the foot pedal, guiding means for holding the connecting means engaged with the operating lever in the downward movement of the lever, means to disengage the connecting means from the operating lever when the foot pedal starts in its upward movement, means for bringing the operating lever back to its uppermost position independently of the foot pedal and the connecting means as soon as the lever is disengaged from the connecting means, means for holding the foot pedal and the connecting means near their lowermost position until the operating lever has reached its uppermost position after being disengaged, and guiding means for bringing the connecting means to a point above the operating lever when the foot pedal is completing its upward movement so as to interengage the foot pedal again with the operating lever.
- 50 8. In an automatic information device, a series of tables, a hand lever, means operative by the hand lever to move the tables to bring any of them into selective position, a foot pedal, means to raise the selected table out of selective position, means to hold the foot lever inoperative, means to release said holding means, and means operated by depression of the said foot pedal to line up and lock the tables against motion.
- 55 9. In an automatic information device, a series of tables, a foot pedal, means to move the tables to bring any one of them into selective position, means to raise the selected table from selective position, a spring, means connecting the spring to the table-raising means and to the foot pedal and operative by depression of the foot pedal to store up energy in the spring and

operative by the stored up energy of the spring when the foot pedal is depressed sufficiently to operate the table-raising means, and means operative by depression of the 5 foot pedal to line up and lock the table-moving means.

10. In an automatic information device, a series of cards, a card carrier, a hand lever, means operative by the hand lever to move 10 any one of the cards to selective position, a foot lever, an operating lever, connecting means between the foot lever and the operating lever adapted to disengage from the operating lever when the foot lever 15 starts to move upwardly, means operative by the downward movement of the operating lever to move the selected card out of selective position to view position, means for locking the card within the removing 20 means as soon as the card leaves the selective

position adapted to free the card as soon as returned to selective and storing position, means for holding the foot lever near its lowermost position until the operating lever has reached its uppermost position and 25 therewith returned the card to storing position, means to bring the connecting means and therewith the foot pedal again into engagement with the operating lever, and means to rest the card removing means and 30 thereby opening the locking means for freeing the card in the storing position after returning from view position.

In testimony that I claim the foregoing as my invention I have signed my name in the 35 presence of two subscribing witnesses.

WILLIAM C. CUTLER.
